UNITED STATES PATENT OFFICE.

HENRY W. HIRSCHFELD, OF MERIDEN, CONNECTICUT, ASSIGNOR TO THE MERIDEN BRITANNIA COMPANY, OF SAME PLACE.

DESIGN FOR A SPOON, &c.

SPECIFICATION forming part of Design No. 22,525, dated June 13, 1893.

Application filed May 15, 1893. Serial No. 474,357. Term of patent 7 years.

To all whom it may concern:

Be it known that I, HENRY W. HIRSCHFELD, of Meriden, in the county of New Haven and State of Connecticut, have invented a new Design for the Handles of Spoons, Forks, &c.; and I do hereby declare the following, when taken in connection with the accompanying drawing and the letters of reference marked thereon, to be a full, clear, and exact description of the same, and which said drawing constitutes part of this specification, and represents a face view.

This invention relates to a design for the handles of spoons, forks, and like articles of table-service, and the design consists in the configuration and ornamentation of the handle as shown in the accompanying illustration.

The tip A, is of an elongated shield-shape, the lower end of the shield resting upon the gradually tapering handle-portion B, the edges of which curve slightly inward, then outward, and then inward, when they merge into the body or bowl of the spoon.

The shield-shaped tip A, has an elongated central panel a upon its outer face, slightly wider at its lower than at its upper end, and surmounted by volute scrolls a' , surrounding

an oval medallion a^2 , having its surface ornamented by checker-work a^3 . At the edges 30 of the central panel a , is a narrow beading b , which is bordered by a shell-like scroll c forming the outer edges of the shield-shaped tip A, and dying out at the lower end, where the panel is represented as overlapped by scroll-work, 35 surmounting a medallion C, forming the lower portion of the shield, and having upon its surface interlaced fret-work d . Below the shield-shaped tip, the handle B, is ornamented by scrolls e , below which is a ribbon f , formed into a loop, its ends then extending parallel along the narrow portion of the handle to near the bowl, where they cross each other at an angle, and branch out into scrolls g . 40

I claim—

The design for the handles of spoons, forks, &c., as described and shown in the accompanying illustration.

In testimony whereof I have signed this specification in the presence of two subscribing witnesses.

HENRY W. HIRSCHFELD.
